UNITED STATES PATENT OFFICE.

JOHN MARRINAN, OF WASHINGTON, DISTRICT OF COLUMBIA.

GROUND ANCHOR.

Application filed May 4, 1926. Serial No. 106,628.

This invention relates to ground anchors adapted for anchoring guy ropes or cables, the invention being especially designed as a substitute for tent stakes, or for anchoring 5 the guy wires of poles, awnings and the like.

An object of the present invention is to provide an anchor in which the tension of the cable or wire will act to force the anchor into the earth, so that increased tension or 10 pull upon the cable or wire will serve to increase the resistance offered by the anchor.

With the above and other objects in view, the invention further includes the following novel features and details of construction, to 15 be hereinafter more fully described, illustrated in the accompanying drawings and pointed out in the appended claims.

In the drawings:—

Figure 1 is a view illustrating the manner 20 of use of the invention.

Figure 2 is an enlarged side elevation of the anchor, the full lines showing the normal position of the parts and the dotted lines a different position.

Figure 3 is a top plan view of the anchor.

Figure 4 is a bottom plan view of a fragmentary section showing the movable member locked.

Referring to the drawings in detail where- 30 in like characters of reference denote corresponding parts, the invention as shown comprises a pair of ground engaging members 10 and 11. The member 10 is of staple-like formation and includes a long ground en- 35 gaging or ground penetrating prong 12 and a relatively short ground engaging or ground penetrating prong 13, a bar 14 serving to connect said prongs.

The member 11 may be constructed of a 40 single length of material bent intermediate its ends to provide a hook 15. This hook is adapted to have attached thereto a rope or cable 16, which may represent a guy rope for a tent, awning or the like, or a guy rope or wire for a mast, or pole. The hook 15 is at the outer end of a short arm 17 which is normally arranged at an angle of substantially forty-five degrees with respect to the prong 12 of the member 10. The member 11 45 is pivotally mounted upon the bar 14 of the member 10 as shown at 18 and the opening in the bar 14 through which the pivot pin 18 extends, may be relatively large so as to permit of free rocking movement of the member 11 upon the member 10. Extending from the arm 17 are oppositely and outwardly in-

clined curved penetrating prongs 19, the shape of which is such that the bar 14 will be disposed tangentially with respect to the prongs 19 when the member 11 is in its normal position. The penetrating ends of the prongs 19 extend downwardly and toward the prong 12, so that when a pull or tension is exerted upon the cable 16, the member 11 will be rocked upon its pivot 18 and the prongs 19 forced into the earth. Resistance of the anchor will thus be increased proportionate to the pull or strain upon the cable.

Pivottally mounted upon the under side of the bar 14 as shown at 20, is one end of a 70 latch bar 21. The opposite end of this latch bar is adapted to engage beneath one of the prongs 19 and when so engaged, will hold the member 11 against pivotal movement. The latch 21 holds the prongs 19 against 75 movement toward the prong 12, while engagement of the arm 17 with the prong 12 will hold the member 11 against pivotal movement in an opposite direction. This serves to lock the members 10 and 11 against 80 relative movement when not in use, or, when the anchor is being initially forced into the ground.

The invention is susceptible of various 85 changes in its form, proportions and minor details of construction and the right is herein reserved to make such changes as properly fall within the scope of the appended claims.

Having described the invention what is claimed is:—

1. A ground anchor comprising a staple-like ground engaging member having a long prong and a relatively short prong spaced therefrom, a second relatively movable ground engaging member carried by the first mentioned member and including ground penetrating prongs and a cable attaching hook rigid with said prongs and means associating said members to force the penetrating prongs of the second mentioned member 95 into the earth under tension of an attached cable.

2. A ground anchor comprising a staple-like ground engaging member having a long prong and a relatively short prong spaced 105 therefrom, a second relatively movable ground engaging member carried by the first mentioned member and including spaced ground penetrating prongs positioned upon opposite sides of the staple-like member and a cable attaching hook rigid with said prongs and means associating said members to force 110

the penetrating prongs of said second member into the earth under tension of an attached cable.

3. A ground anchor comprising a staple-like ground engaging member terminating in an integral long prong and also in an integral relatively short prong spaced therefrom, ground penetrating prongs movably connected with the staple-like member and means to attach a cable to the anchor whereby tension of said cable will force the prongs into the earth.

4. A ground anchor comprising a staple-like ground engaging member having a long prong and a relatively short prong spaced therefrom, oppositely inclined outwardly extending prongs mounted upon the staple-like member and a cable attaching hook rigid with said prongs and means associating said members to force the penetrating prongs of the second mentioned member into the earth under tension of an attached cable.

5. A ground anchor comprising a pair of ground engaging members, one of said mem-

bers including straight substantially parallel ground penetrating prongs and the other member including curved ground engaging prongs, means to attach a cable to the last referred to member and means to associate the members whereby tension of an attached cable will force the prongs of one member into the earth.

6. A ground anchor comprising a pair of ground engaging members, each of said members including ground penetrating prongs, means to attach a cable to one of the members, means to pivotally associate the members whereby tension of an attached cable will force the prongs of one member into the earth and means to lock the members against relative pivotal movement.

7. A ground anchor comprising spaced prongs connected together at their heels, other prongs movably connected with the first-named prongs, and cable-attaching means connected with the second-named or other prongs.

In testimony whereof, I affix my signature.

JOHN MARRINAN.
